J. M. LEA

ELECTRIC CIRCUIT CONTROLLING DEVICE

Filed April 13, 1922

Inventor
John M. Lea
By his Attorney
G. A. Lovett

UNITED STATES PATENT OFFICE.

JOHN M. LEA, OF DETROIT, MICHIGAN.

ELECTRIC-CIRCUIT-CONTROLLING DEVICE.

Application filed April 13, 1922. Serial No. 552,396.

The invention relates to devices for controlling and protecting electric circuits and more particularly for preventing injury to parts and excessive loss of current in electric systems upon the occurrence of short circuits therein. While in some respects not limited to such use, it is of especial utility in connection with electric systems such as are employed in motor vehicles and which include 5 a storage battery for the supplying of current to electric starting, lighting and ignition devices.

The principal object of the invention is to provide new and improved means adapted to 15 be heated by electrical energy and operative upon excessive flow of current to interrupt the circuit in which such flow occurs. In one embodiment of the invention such interruption may be accompanied by the insertion in 20 series in the protected circuit of a heating coil which maintains the circuit breaker in position to prevent further heavy discharge until the short circuit is remedied, thus reducing to a minimum the total loss of energy. 25 In another embodiment the interruption may be complete but only temporary, recurring immediately, however, as soon as the circuit is again closed should the short circuit still remain in effect. Means may also be provided whereby, upon the operation of the circuit breaker, a signal will be actuated to indicate the occurrence of a short circuit or of 30 an abnormally high rate of current flow. Such signal is preferably arranged to be actuated intermittently and means may be provided to prevent injury to the thermally actuated circuit breaker should the signal circuit also contain a short circuit.

The circuit interrupting devices are preferably so constructed and arranged as to permit of their insertion in place of fuses or like protective devices in circuits where the latter are generally employed and are particularly suitable for circuits operating under relatively low voltage and of non-inductive character such, for example, as those of motor vehicle lighting and ignition systems. For this purpose the circuit interrupting means is preferably embodied in a self contained 45 unit of such form and size that it may be mounted between fuse clips of conventional character, the fuses being rendered unnecessary by the use of the improved device; or 50 may be otherwise removably mounted in place of analogous protective mechanisms.

Further objects and advantages will appear from the following description taken in connection with the accompanying drawings in which

Fig. 1 is a plan view of one form of device in which the invention may be embodied,

Fig. 2 is a longitudinal section on line 2—2 of Fig. 1,

Fig. 3 is a transverse section on line 3—3 of Fig. 2,

Fig. 4 is a plan view of another embodiment of the invention,

Fig. 5 is a section on line 5—5 of Fig. 4,

Fig. 6 is an end elevation of the structure shown in Fig. 4 looking from the right of 70 Fig. 4,

Fig. 7 is a wiring diagram illustrating the application of the device shown in Figs. 1, 2, 3,

Fig. 8 is a wiring diagram illustrating the application of the device shown in Figs. 4, 5, 6, and

Fig. 9 is a wiring diagram illustrating a slight modification.

Referring first to the structure shown in Figs. 1 to 3, 11 indicates a plate of suitable conducting material such as brass, which plate is bent upwardly adjacent to one end to form wings 12, 13, adapted to fit between and be firmly held by the arms of a spring clip 14. A second conducting plate 15 secured to the plate 11 at one end is formed at the other end with wings 16, 17, similar to the wings 12, 13, and adapted to fit between the arms of a second spring clip 18. The clips 14, 18, are of a type commonly employed for the mounting of fuses, which latter may be replaced by the device illustrated, and will be suitably connected in series with the circuit to be protected.

The adjoining ends of the plates 11 and 15 are superposed and secured together in any convenient manner as by lugs or flanges 19 on the plate 11 which are bent over the plate 15, as shown. A sheet of insulating material 20 is interposed between the plates and preferably covers the entire inner surface of the plate 11. A blade 21 of bimetallic thermostat material is clamped upon the end of the plate 15 and in conducting relation thereto as by the lugs 19, the insulating material 20 preventing contact of the blade with the said lugs. The blade is properly positioned by providing holes 22 therein which fit over slight projections 23 struck up from the 90

100

105

110

plate 15. The free end of the blade extends over the plate 11 and carries at its extremity a contact 24 so positioned as to engage normally with a contact 25 mounted upon the plate 11. A heating coil 26, which may be of nichrome or similar material, is arranged in heating relation to the blade 21 as by being wound thereon and insulated therefrom and is connected at one end to the blade and at the other end to the plate 11.

The operation of the device already described may be understood by reference to Fig. 7 in which the thermostatic circuit breaker is shown diagrammatically in connection with a circuit including a battery B and one or more translating devices such as lights 29 control of which may be had by means of a switch S. The arrangement is such that the current utilized by the translating devices will flow normally through the blade 21 and the contacts 24, 25. Assuming, however, that a short circuit should occur between the protecting device and the translating devices, as, for example, at the point 30, then the flow of current through the blade upon the closing of the switch S will be greatly in excess of the normal flow. As soon as such flow exceeds that for which the blade is calculated and adjusted the heating effect causes the blade to be deflected and the circuit to be interrupted at the contacts 24, 25, the blade being so mounted that it tends to move away from the contact 25 as the temperature rises.

In the absence of some provision for the maintenance of an elevated temperature affecting the blade 21 the interruption of the circuit will be only temporary, since, as soon as the blade cools sufficiently, the contacts will again engage. Even without such provision the loss of current will be substantially negligible inasmuch as the heating effect due to excessive current is such as to cause almost instantaneous deflection of the blade.

In fact it has been found that continuous operation of the device for several hours does not appreciably lower the battery charge as indicated by hydrometer tests. Means may be provided, however, for maintaining the interruption in effect so long as the abnormal conditions exist as, for example, by the use of the coil 26. The arrangement is such that when the contacts 24, 25, are disengaged by the movement of the blade 21 the heating coil is inserted in series in the protected circuit. The current which then flows through the coil, which is of relatively small value, because of the high resistance of the coil, produces a heating effect the extent of which may be predetermined by selection of the characteristics of the coil.

The coil may operate, therefore, either to heat the blade to such an extent that after the contacts have once separated the blade will remain in deflected position so long as the

short circuit remains in effect, or it may permit initially a few reciprocations of the blade before the heating effect becomes sufficient to maintain the deflection of the blade. Should the heating effect be still less it may operate merely to delay the cooling of the blade so as to render less rapid the return movement to circuit-closing position.

Whether the heating coil is utilized or not, I prefer to arrange some form of signal device in such relation to the system that the abnormal conditions resulting in excessive current discharge may be brought to the attention of the operator. For this purpose the ammeter A may be employed as illustrated, being located between the source of current and the protective device. Very abrupt oscillations of the indicator to its extreme limits of movement will accompany the momentary discharges of current through the protective device and thus advise the operator of the occurrence and nature of the arrangement in the system.

Referring to the form of the invention illustrated in Figs. 4, 5 and 6, 31 indicates a base plate which may be provided with upwardly extending flanges 32, 33, 34, to partially enclose and protect the thermostatic devices mounted upon the plate. An ear 35 extends laterally from the base plate which may serve as a means of attachment of the device to a supporting structure and also to connect the plate to a conductor in the circuit to be protected. A contact plate 36 and two end connector plates 37, 38, suitably insulated from each other and from the base plate 31, are fastened together and to the base plate in any convenient manner, as by rivet 39. Binding screws 40, 41, may be provided to connect the plates 37, 38, respectively to a signal circuit and to the main circuit to be protected. Two contact members 42, 43, of bimetallic thermostatic material are secured in position by the rivet 39, the member or blade 42 being in conducting relation to the connector plate 38 and the blade 43 in similar relation to the plate 37, and both blades being so arranged as to move upwardly when heated, or away from the positions represented in the drawing. A series of contacts 44, 45, 46, and 47 are mounted respectively on the base plate 31 and the free extremities of the members 42, 36 and 43. These contacts are superposed substantially in alignment so that each contact is in position to engage the next adjacent contact either above or below. The parts are normally so positioned that the contacts 44 and 45 will be in engagement and likewise the contacts 46 and 47. The terminal plate 38 is therefore normally in conducting relation with the base plate 31 through blade 42 and contacts 44, 45, while the terminal plate 37 is in conducting relation to the intermediate plate 36 through blade 43 and contacts 46, 47. A heating coil 48 may be arranged in heating relation to the

blades 42 and 43 as by being mounted upon but insulated from the parts 36, 42, the ends of the coil being connected respectively to the blade 42 and the base plate 31. The device as illustrated is especially designed to replace the vibrator employed in certain types of motor vehicle lighting and ignition switches.

The operation of this form of the invention will be understood by reference to Fig. 8, 10 wherein the device is illustrated as applied to a motor vehicle electric system including a battery B, translating devices such as the lamp 49, and a signal device, shown in this instance as a horn 50 which may be the horn ordinarily 15 employed by the driver as a warning signal. The blade 42 is connected in series in the main circuit so that current normally flows to the translating devices through the blade 42 and contacts 45, 44. The blade 43 is connected to 20 the horn. Should the main circuit become grounded at some point between the protecting device and the translating devices, as indicated at 51, a heavy discharge will take place through the blade 42 thus heating it and 25 causing the immediate separation of the contacts 44, 45. The blade is so designed that it practically snaps away from its normal position and into engagement with the fixed intermediate plate 36 whereby it completes a circuit 30 through blade 42, contacts 45, 46, 47, and blade 43 to the horn 50. Disregarding the effect of the coil 48, which may be omitted if desired, the horn will continue to sound for a few seconds or until the cooling of the blade 35 42 causes the separation of the contacts 45, 46. When the blade cools sufficiently to permit the re-engagement of the contacts 44, 45, a momentary heavy discharge will take place 40 through the blade 42 followed by a repetition of the warning signal. Supposing, however, 45 that the signal circuit should become grounded between the protecting device and the horn, as indicated at 52, then the blade 42, when it acted to complete the alarm circuit, 50 would still be subject to heavy discharge of current by reason of the short circuit at 52. Unless some means were provided to prevent it such heavy discharge would quickly fuse the blade and, while this would serve to completely 55 interrupt the circuit, as with an ordinary fuse, it would necessitate the replacement of the device in order to re-establish the working circuit. This inconvenience may be avoided by the use of the blade 43. Should a heavy 60 discharge take place through this blade it will cause separation of the contacts 46, 47, thereby interrupting the signal circuit until the blade again cools. The only effect of a short circuit in both the main and signal circuits, therefore, 65 it will to cause a more or less rapid alternation in the making and breaking of the circuits through the two thermostat blades. The total loss of current through such operation is substantially negligible, whereas the 70 magnetic vibrator which the device is de-

signed to replace usually consumes about eight and one half amperes when in operation.

The operation as above described may be modified by the effect of the heating coil 48. 75 This coil, upon the separation of contacts 44, 45, will act, as in the form first described, to retard the rate of cooling of the thermostats and thereby delay the repetition of the cycles of operation. It may even operate after a 80 certain time interval has elapsed to prevent entirely the return of the thermostats to their original position while the short circuit remains in effect, thus acting, after the signal has been operated for a time, to maintain the 85 circuits open with only the expenditure of the current required for the heating coil, which amount may be exceedingly small.

In Fig. 9 is illustrated diagrammatically 90 a form of the invention similar to that shown in Figs. 1 to 3 but combined with a signal circuit including a horn 50. A back contact 54 is interposed in the signal circuit. Upon the occurrence of a short circuit as indicated at 30, the deflection of the blade 21', similar to the blade 21 of Fig. 1, will result in the closing of a circuit through the horn by way of a fixed contact member 54. The signal will therefore be sounded intermittently so long as the conditions continue which would otherwise permit a heavy discharge of current in the main circuit. No provision is made in this case for protection in the event of accidental grounding of the signal circuit. This form of the invention differs therefore 100 from that shown in Figs. 4, 5, 6 and 8 in the omission of the thermostatic circuit breaker 43, while it adds to the form shown in Figs. 1, 2, 3 and 7 the provision of a back contact 105 operating a signal circuit.

The thermostat blades employed may be of the well-known type comprising a plate of brass and another of iron which is one half the thickness of the brass or less, the two being so secured together that differential expansion of the two plates will cause deflection of the blade. For use in carrying out the present invention the dimensions of the blade and its conducting capacity must be so determined that it will carry all of the normal working current without being heated thereby to such an extent as to cause separation of the contacts. On the other hand, in order to prevent waste of current and injury to other devices in the circuit upon the occurrence of a short circuit, the thermostat should be sufficiently sensitive to be deflected substantially instantaneously under the influence of excessive discharge. Furthermore, if the blade is designed for quick response to heavy flow of current it would be readily fused should such flow continue for an appreciable time and this also necessitates quick interruption of the circuit if the blade is to be preserved.

Bimetallic blades of the type mentioned are 130

peculiarly adapted to perform the required function because, after the predetermined critical current flow has been exceeded, the temperature rises very rapidly, due, possibly, 5 not only to increased resistance accompanying the rise in temperature but also to the different conductivities of the two metals as a result of which the greater part of the discharge takes place through the brass and 10 thereby disproportionately increases the temperature of the latter and its rate of expansion. Tests made with a blade so proportioned that it would carry approximately 14 amps. without breaking the circuit have 15 shown that a discharge resulting from the short circuiting of an ordinary automobile starting and lighting battery through the blade will produce what may be properly termed a "snap" action causing the blade not 20 only to interrupt the main circuit very abruptly but to continue its movement after the circuit is actually broken and thereby engage the contact in the signal circuit and remain in engagement therewith for an appreciable time.

It will be understood that a signal may be given upon the occurrence of a short circuit in various ways other than those above described, as by means of the vehicle lights or 30 other lighting devices or by other visible or audible means. The protecting device may also be mounted in a transparent casing within view of the operator so that the flashes due to separation and re-engagement of the contacts will be visible. Various other modifications in details of construction and operation may be made without departing from the spirit and scope of the invention and therefore I do not wish to be limited to the 35 40 features as described except as required by the language of the claims in view of the prior art.

I claim:

1. An electric circuit controlling device 45 comprising a conducting base member, a second conducting member mounted upon said base member and insulated therefrom, and a thermostat blade secured at one end in conducting relation to said second member and 50 having its free end normally in conducting relation to said base member, and a heating coil mounted in heating relation to said thermostat and arranged to be traversed by current upon the separation of said contacts.
2. An electric circuit controlling device 55 comprising a conducting member adapted to be connected in an electric circuit, a second conducting member secured to the first but insulated therefrom and adapted to be connected in said circuit, a thermostatic blade secured in conducting relation to one of said members and insulated from the other, co-operating contacts on said other member and

the free end of said blade and a heating coil wound upon said blade and having its ends 65 connected respectively to said conducting members.

3. In means for protecting an electric circuit, the combination with a conductor of said circuit of a conducting element in series therewith, heat-responsive means adapted to cause movement of said element and thereby interrupt said circuit and a heating element arranged in heating relation to said heat-responsive means and so related to said circuit 70 as to continue to be heated during the interruption of said circuit, said heating element arranged to exert an influence tending to oppose the return of said element to circuit-making position.

4. In means for protecting an electric circuit, the combination with a conductor of said circuit of a pair of contact members in said circuit, a thermostatic element arranged to cause separation of said contact members 85 upon the occurrence of abnormal flow in said circuit, and a heating coil arranged in shunt with said members and in heating relation to said element, the connections being so arranged that heating current continues to flow 90 in said coil after separation of said contact members.

5. In means for protecting an electric circuit, the combination with a conductor of said circuit of a circuit-interrupting device therefor constructed and arranged to move normally towards circuit-closing position, heat-responsive means adapted to cause movement of said device to interrupt said circuit upon the occurrence of excessive flow therein, and means tending to oppose return of said device 95 to circuit-closing position during the continuance of the abnormal condition tending to cause such excessive flow.

6. The combination with an electric circuit of mechanism for preventing continued excessive current flow therein comprising a pair of contacts in said circuit, a current conducting thermostat in said circuit arranged to cause separation of said contacts by movement of the thermostat due to temperature increase, said thermostat being so proportioned relative to the maximum excessive current whose continuance is to be prevented that it will be given substantially a snap action by 100 passage therethrough of the said current, a second pair of contacts arranged to be closed by movement of said thermostat after separation of the first pair and means for causing intermittent interruption of current flow 110 through said second pair of contacts so long as they tend to be held closed by the action of said thermostat.

In testimony whereof I affix my signature.

JOHN M. LEA.
